SWITCH

Ernst Walter Rickmeyer, Elmhurst, Ill., assignor
to Jefferson Electric Company, Bellwood, Ill.,
a corporation of Illinois

Application April 8, 1944, Serial No. 530,123

11 Claims. (Cl. 200—80)

1

The present invention relates to switches and more particularly to centrifugal switches where-
in a conducting fluid (mercury) is moved by cen-
trifugal force to control the flow of current in a
circuit. In such devices the conducting fluid is
confined in a shell which may serve as one ter-
minal contact. The other terminal contact may
comprise a contact member that opens into the
shell at one end thereof and is insulated from the
shell.

The switch functions to time the circuit change
in response to the centrifugal force set up in the
shell by the rotation of the carrier for the shell.
The timing is accomplished by utilizing a re-
stricted passage or a plurality of restricted pas-
sages through which the conducting fluid must
flow under the pressure developed by the cen-
trifugal force.

The present invention concerns itself with a
novel switch construction whereby the passage or
passages can be provided in a simple manner that
lends itself to accurate and rapid production.

In the production of switches of the character
hereinbefore described it is essential that the de-
vices have uniformity of timing, simplicity and
ruggedness of construction. In one form of switch
to which my invention applies a tubular shell is
divided into two chambers, one of which, before
actuation of the switch, is completely filled with
the conducting fluid. The other chamber acts
as a receiver for the conducting fluid. The pas-
sage restriction is located in a member inter-
posed between the two chambers and is so ar-
ranged as to pass the conducting fluid at a rate
dependent upon the pressure of the fluid against
said member, the pressure in turn being respon-
sive to the centrifugal force set up by rotation of
the shell about an axis at or near the filled end
thereof.

In this form of device the shell is a metal shell
which is mounted upon a rotating or spinning
device with the filled end of the shell toward the
axis of rotation. The restriction member is
spaced radially from a contact member within
one end of the shell. It is evident that the rota-
tion or spinning of the supporting member for
the shell will force the conducting fluid through
the passage or passages in the restriction member
into the receiving chamber until the shell and
the contact member are connected by means of
the conducting fluid if the contact member is
in the outer end of the receiving chamber and
therefore farther from the axis of rotation than
the restriction member. However, when the con-
tact member is closer to the axis of rotation than

the restriction member the passage of the con-
ducting fluid outward into the receiving chamber
will cause a break between the conducting liquid
and the contact member.

It is also a purpose of this invention to provide
a novel means whereby a multiplicity of very
fine restricted passages may be formed interme-
diate the ends of the shells in a switch of this
character by the utilization of a fibrous mate-
rial in conjunction with a solid support provided
with one or more apertures that are covered by
the fibrous material.

It is a further purpose of the invention to pro-
vide in a device of this character a novel means
for clamping and securing an apertured support
with a layer of fibrous material in transverse
position within a shell.

Other detailed objects and advantages of the
invention will appear as the description proceeds,
reference being had to the accompanying draw-
ings wherein a preferred form of the invention is
shown. It is to be understood however that the
drawings and description are illustrative only and
are not to be taken as limiting the invention ex-
cept insofar as it is limited by the claims.

In the drawings:

Fig. 1 is a plan view of a rotating device where-
in a circuit controlling switch of the type em-
bodying my invention is mounted;

30 Fig. 2 is a longitudinal sectional view through
the switch itself;

Fig. 3 is a plan view of the switch shown in
Fig. 2;

Fig. 4 is a sectional view taken on the line 4—4
35 of Fig. 2;

Fig. 5 is a view like Fig. 1 but showing a modi-
fied form of switch mounted in the rotating mem-
ber;

Fig. 6 is a longitudinal sectional view through
40 the switch shown in Fig. 5;

Fig. 7 is an end view of the switch shown in
Fig. 6; and

Fig. 8 is a sectional view taken on the line 8—8
45 of Fig. 6.

Referring now in particular to Figs. 1 to 4, in-
clusive, I show in Fig. 1 a rotating element 10
which may be mounted upon any suitable power
means such as the shaft of a motor. The mem-
ber 10 has a pocket 11 therein which receives a
50 switch element 12. My invention is particularly
concerned with the switch element 12 and the
means for breaking contact between its two ter-
minals 13 and 14. The switch element 12 com-
prises a metal shell 15 to which the terminal 13
55 is welded or otherwise secured. A central con-

tact member 16 is supported at one end of the shell and the terminal 14 is attached to the contact member 16.

It will be noted from an inspection of Fig. 1 that the switch is arranged with the end of the shell 15 that carries the central contact 16 closest to the axis of rotation of the member 10. In rotation therefore centrifugal force will be set up lengthwise of the shell 15 in a downward direction as it is shown in Fig. 2. I divide the shell 15 into a chamber 17 and a chamber 18 by providing a transverse partition below the inner end of the contact member 16. The chamber 17 is initially filled with a conducting fluid such as mercury so that a closed circuit exists between the terminals 13 and 14. The chamber 18 is empty of the fluid and by providing a restricted passage or passageways between the chambers 17 and 18 the length of time the circuit will remain closed can be controlled in response to the centrifugal force set up by rotating the switch 12 by means of the member 10. My invention concerns itself with the provision of a novel construction whereby the restricted passage between the chambers can be provided.

In order to provide restricted passage between the chambers 17 and 18 I set an inverted cup 19 within the bottom of the shell 15 and provide this cup with a central aperture 20 of a definite size dependent upon the rate at which it is desired to pass the mercury from the chamber 17 to the chamber 18 at a given speed of rotation of the member 10. On the side of the aperture 20 toward the axis of rotation I then provide a layer 21 of porous material and I clamp this layer of porous material against the surface of the cup 19 around the aperture 20 by means of a clamping member 22.

The cross sectional area of the aperture 20 is quite critical. This area and the porosity of the layer 21 determine the rate of flow of mercury out of the chamber 17. Any slight increase in the diameter of the aperture 20 effects a substantial increase in total area of the aperture 20 and opens a larger number of passages through the porous material, thereby decreasing the time it will take to pass enough mercury to break contact with the contact member 16.

The layer of porous material 21 preferably is made up of an intermediate layer 23 of fibrous material such, for example, as blotting paper wherein the fibers are of sufficient length that they will bridge the aperture 20. Blotting paper is mentioned merely as an example, as other felted fibers may be used. This intermediate layer is confined between two covering layers 24 and 25 of linen or other woven fabric to give support to the blotting paper.

The clamping member 22 has a central aperture 26 which is slightly larger than the aperture 20. This clamping member is cupped as shown in Fig. 2 and in order to cause it to hold the layer 21 of fibrous material under pressure against the face of the member 19 the shell 15 is rolled inward as indicated at 27. This rolling operation forces the member 22 toward the member 19 and thus effects the desired pressure clamping of the layer 21 over the aperture 20.

It will be noted that the contact member 16 is mounted by two insulating disks 28 and 29. These disks may be made of any suitable insulating material such as polystyrene. The shell is provided with a shoulder at 30 to receive the insulating washer 28 and is then rolled or spun over as indicated at 31 to lock the washer in place and

complete the sealing of the shell 15. The material of the shell in the form shown is a suitable deep drawing steel that can be readily made to the shape desired, and the center contact member 16 may be ordinary cold rolled steel. Various other materials may be used for these parts. For example, the shell has been made of Armco iron and the same material has been used for the contact member 16. The iron and steel do not amalgamate with the mercury to any great extent and are advantageous for that purpose where the amalgamation might adversely affect the operation of the device. The members 19 and 22 may also be made of steel or Armco iron and the contact member 16 may be made of stainless steel, copper, Monel metal or any other suitable conductor material.

In operation the rotation of the shell by the member 10 causes the mercury to be forced through the porous material 21 that is directly over the aperture 20. The porosity of the material, the size of the aperture 20 and the pressure developed by the centrifugal force determine the rate at which the mercury will escape from the chamber 17. The central contact 16 and the shell are of such size that before the mercury fills the chamber 18 it will pass the inner end of the contact 16 and thus open the circuit. However, owing to the fine porosity of the porous material 21 the mercury normally will not escape through this material into the chamber 18 due to the jolts and tumbling that the device undergoes in normal handling. The switch as shown is a one time switch. In other words, once the switch operates a circuit is broken until the rotation stops. Before the switch can again be used the conducting fluid in the chamber 18 must be forced back into the chamber 17. This can be accomplished by the simple method of reversing the switch end for end, and rotating it by means of the member 10.

Referring now to Figs. 5 to 8, inclusive, in this form of the device means are provided whereby a simple shell with two transverse disks may be utilized to obtain the same results as are obtained by the construction shown in Figs. 1 to 4, inclusive, with the added advantage that considerable machine work is avoided on the shell and the volume of the chamber around the center contact is materially reduced, thus reducing the amount of conducting fluid necessary.

In this form of the invention a shell 32 is originally drawn and is then provided with an inwardly extending bead 33 which may be formed by a rolling operation. Then an apertured disk 34 provided with an aperture 35 of the desired cross section is placed against the shoulder provided by the bead 33 and a layer 36 of porous material exactly like the layer 21 of Figs. 1 to 4 is placed over the disk 34. A clamping disk 37 is then placed over the layer 36. This clamping disk is provided with an aperture 38 that is aligned with and slightly larger than the aperture 35. A center contact 39 is then seated within the shell and by means of a rolling operation the shell portion 32a between the disk 37 and the insulating disk 40 which supports the center contact 39 is forced inward so as to clamp the disks 34 and 37 together over the layer 36 of porous material. This rolling operation on the portion 32a of the shell is carried out to the extent desired to give the right size of chamber 17' about the center contact 39. Likewise this rolling operation serves as a means of accurately spacing the end of the contact member 39 from the aperture 35. The chamber 18' is formed by

the closed end of the shell 32 and the disk 34. The washer 40 which supports the center contact 39 is sealed in place by rolling over an edge 41 at the open end of the shell.

This particular construction has the advantage that necessity for making the orifice carrying member cup-shaped is avoided. Likewise the rolling operation provides a shoulder for the disk 40 and thus eliminates the necessity for cutting the shoulder on the inner surface of the shell at the open end as indicated at 30 in Fig.

2. Terminals 42 and 43 for the contact 39 and the shell 32 may be provided in the same fashion as the terminals 13 and 14 are provided. The operation of this form of the device is essentially the same as that shown in Figs. 1 to 4 but in this form the volume of the chamber 17' can be more accurately controlled.

In the specific description of the forms of device shown I have referred only to a switch 20 wherein the centrifugal force acts to open the circuit. It is obvious however that the same type of switch can be used to close a circuit by forcing a conducting fluid through a restricting member having restricted passages therein, the particular feature of my invention being in the construction of the switch so that the restricted passages may be provided in an accurate, uniform manner in mass production. All of the operations on the shell and its contained parts can be done with automatic machinery so as to make the ultimate product at a low cost.

In the description and in the claims I refer to the switch member as being radially disposed with respect to the spinning or rotating member. This term is meant to include placing the tubular member with its axis in a plane intersecting the axis of rotation of the member 10 since it is evident that the switch could still function if the axis of the shell did not coincide with a radius from the axis of the member 10. In the preferred constructions as described I have also shown the shell as being of conducting material and forming one of the contacts of the switch. This obviously is not necessary since the one contact might be provided in a shell of insulating material and the same general results obtained. Such a construction is contemplated in my invention.

From the foregoing description it is believed that the nature and advantages of my invention will be readily apparent to those skilled in this art.

Having thus described my invention, what I claim as new and desire to secure by Letters Patent is:

1. A switch comprising a spinning member, a tubular shell radially disposed thereon, a contact member at one end of the shell and sealed thereto, the other end of the shell being closed, and a restriction member across said shell between the contact member and the closed end thereof, said restriction member comprising a support having at least one aperture therein, a layer of porous material on the side of said restriction member facing the axis of rotation, and a clamping member on the side of said layer facing the axis of rotation and holding the layer of porous material under pressure against the support.

2. A switch comprising a spinning member, a tubular shell radially disposed thereon, a contact member at one end of the shell and sealed thereto, the other end of the shell being closed, and a restriction member across said shell between the

contact member and the closed end thereof, said restriction member comprising a support having at least one aperture therein, a layer of porous material on the side of said restriction member facing the axis of rotation, and a clamping member on the side of said layer facing the axis of rotation and holding the layer of porous material under pressure against the support, said layer of porous material including fibrous material having fibers of a length sufficient to extend across the aperture.

3. A switch comprising a spinning member, a tubular shell radially disposed thereon, a contact member at one end of the shell and sealed thereto, the other end of the shell being closed, and a restriction member across said shell between the contact member and the closed end thereof, said restriction member comprising a support having at least one aperture therein, a layer of porous material on the side of said restriction member facing the axis of rotation, and a clamping member on the side of said layer facing the axis of rotation and holding the layer of porous material under pressure against the support, said layer of porous material comprising a layer of fabric next to the support, a felted fibrous material layer over said fabric layer and another fabric layer over the fibrous material.

4. A switch comprising a spinning member, a tubular shell radially disposed thereon, a contact member at one end of the shell and sealed thereto, the other end of the shell being closed, and a restriction member across said shell between the contact member and the closed end thereof, said restriction member comprising a support having at least one aperture therein, a layer of porous material on the side of said restriction member facing the axis of rotation, and means clamping said layer of porous material to the support.

5. In a centrifugal switch of the character described, a tubular shell, a contact member extending into said shell at one end thereof, insulating means supporting said contact member and sealed to said shell, the other end of the shell being closed, transversely extending members intermediate the ends of said shell providing a partition separating the shell into two chambers, said transversely extending members including means providing a restricted passageway from one chamber to the other, and said shell having an inwardly extending bead pressed against one of the members whereby to hold them in assembled relation.

6. In a switch of the character described, a tubular shell having one end closed, a contact member extending into the shell from the other end, an insulating washer supporting said contact member and closing the end of said shell, a cup-shaped member seated in the other end of the shell with its base spaced from the end of the shell and provided with an aperture, a layer of porous material on said cup-shaped member, a clamping member on said layer of porous material, and an inwardly extending bead in the shell wall forcing the clamping member against the porous material.

7. In a switch of the character described, a tubular shell having an inwardly extending bead adjacent one end thereof, said end of the shell being closed, an apertured disk seated on said bead on the side opposite the closed end of the shell, a layer of porous material on the apertured disk, and means including an inturned portion 75 of the shell and a second apertured disk holding

the layer of porous material against the first named apertured disk.

8. In a switch of the character described, a tubular shell having one end closed and having a portion of restricted diameter adjacent said end, a restricted passageway forming means resting on said portion of restricted diameter, said shell having a second portion of restricted diameter holding said restricted passageway forming means in position, a contact member extending into the shell from the other end thereof, an insulating support for said contact member, said shell having a shoulder at the last named end thereof on which said support rests, the open end of the shell being turned over the insulating support to secure the contact rigidly in the shell.

9. In a switch of the character described, a tubular shell adapted to be rotated about an axis adjacent one end thereof, a contact member at one end of the shell and sealed thereto, the other end of the shell being closed, and a restriction member across said shell between the contact member and the closed end thereof, said restriction member comprising a support having at least one aperture therein, a layer of porous material on the side of said restriction member facing the axis of rotation, and a clamping member on the side of said layer facing the axis of rotation and holding the layer of porous material under pressure against the support.

10. In a switch of the character described, a tubular shell adapted to be rotated about an axis adjacent one end thereof, a contact member near one end of the shell and sealed thereto, a restriction member extending across the shell and spaced from the contact member, said restriction member comprising a support having an aperture therein, a layer of porous material on the side of the restriction member facing the axis of rotation, and a clamping member having an aperture slightly larger than the aperture in the restriction member and holding the layer of porous material under pressure against the support.

11. In a switch of the character described, a tubular shell adapted to be rotated about an axis adjacent one end thereof, a contact member near one end of the shell and sealed thereto, a restriction member extending across the shell and spaced from the contact member, said restriction member comprising a support having an aperture therein, a layer of porous material on the side of the restriction member facing the axis of rotation, and a clamping member having an aperture slightly larger than the aperture in the restriction member and holding the layer of porous material under pressure against the support.

12. In a switch of the character described, a tubular shell adapted to be rotated about an axis adjacent one end thereof, a contact member near one end of the shell and sealed thereto, a restriction member extending across the shell and spaced from the contact member, said restriction member comprising a support having an aperture therein, a layer of porous material on the side of the restriction member facing the axis of rotation, and a clamping member having an aperture slightly larger than the aperture in the restriction member and holding the layer of porous material under pressure against the support, said layer of porous material comprising fibers of a length sufficient to bridge the aperture in the support.
